Primary Examiner — Darlington Ly*Assistant Examiner* — Giang Hoang Tran(74) *Attorney, Agent, or Firm* — Husch Blackwell(57) **CLAIM**

The ornamental design for a modular lubrication dispensing unit as shown and described.

DESCRIPTION

FIG. 1 is a top, front and right side perspective view of a modular lubrication dispensing unit showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is an exploded, front perspective view thereof.

The broken lines in the drawings illustrate portions of the modular lubrication dispensing unit that form no part of the claimed design.

1 Claim, 8 Drawing Sheets(56)
